UNITED STATES PATENT OFFICE.

BYERS W. KADEL, OF BALTIMORE, MARYLAND.

RAILWAY CAR.

Application filed March 18, 1924. Serial No. 699,986.

The invention relates to railway cars and has as its principal object to provide improvements in the door construction of the same. One of the objects is to provide an improved arrangement of door stiffener or door spreader, with door securing means carried thereby. Another object is to provide improved means for supporting the doors in partially or fully closed position. A still further object is to provide means for forcing such doors shut and for locking them in closed position. With such objects and others in view, the invention consists of the formation, combination and arrangement of parts as will be herein described and finally claimed.

In the accompanying drawings which show a preferred form of the invention, Figure 1 is a side elevational view of a portion 20 of a railway car having a door mechanism constructed in accordance with the principles of the present invention. Figure 2 is a fragmentary end elevational view taken in the direction of arrow A, Figure 1, and showing a portion of the hopper and door, together with the door supporting mechanism. Figure 3 is a transverse vertical cross-sectional view through the door spreader or door stiffening member, this view being taken on line 3-3 of Figure 2. Figure 4 is a transverse sectional view taken through a portion of the car and door, this view being taken on the line 4-4 Figure 1. Figure 5 is a fragmentary side elevational view of the hopper of the car, this view being similar to Figure 1, but showing the door in partially closed position instead of in fully closed position. Figure 6 is a vertical sectional view taken through a portion of the locking mechanism, this view being taken on the line 6-6, Figure 2. Figures 7, 8 and 9 are perspective views respectively of the preliminary latching member, the final latching member and the fixed hook or ledge carried by the car body.

The car chosen for illustration of the invention is of the ordinary twin hopper type such as is well known in the art. The side of the car or the hopper end sheet is denoted by numeral 1. It is shown in the drawings as provided with a sealing flange 2 along the side and bottom of the discharge opening, the offset 3 comprising a seat for the door 4. The door is hinged at 5 to any suitable portion of the car body, the hinge pintles extending transversely of the car and the door being

arranged to swing open by gravity for the discharge of the lading. Near the lower or free edge of the door there is secured to the outer face of the same a stiffening member 6 which extends transversely of the car, and in cases where individual hoppers are supplied at either side of the center sill construction of the car, this member may constitute a door spreader for uniting the two members 65 of the door. This door stiffening member 6 is preferably formed of a channel or U-shaped section having a web portion 7 arranged to lie in a plane parallel with the plane of the door plate. Securing rivets 8 70 may be passed through holes in this web and through the door plate for securing the stiffener directly against the outer face of the door. The flange or web members 9 of the channel or U-shaped section extend outwardly from opposite edges of the web portion 7 thereof, and at the outermost edges of these flange or web portions 9 there are formed in the present embodiment, return flanges 10 which stiffen the edges of the main flanges or 80 webs 9, these return flanges 10 being arranged in a plane parallel with that of the web 7.

The door 4 is preferably formed of a steel plate with marginal flanges 11 formed around its edges in order to stiffen the door plate. 85 The end of the stiffening member 6 terminates slightly inwardly of one of the marginal flanges 11 and door supporting members are carried by the stiffener and comprise an extension thereof, these overlying the 90 flange 11 so as to reach out slightly beyond the side of the car in order to cooperate with supporting means that is attached to the side of the car.

The supporting means that is carried by 95 the side of the car consists, in the present embodiment, of a bracket 12 which is riveted to the hopper end sheet by means of rivets 13. This bracket is offset at 14 to pass around the shoulder 3 of the hopper end sheet and then extends outwardly along the flange 2 thereof. Near its outer end this bracket is provided with a ledge 15 adapted to be engaged by pivoted door supporting members 16 or 17 mounted upon the door. Outwardly 105 of the ledge 15 this bracket is provided with an approach portion 18 arranged to lift either of the latches 16 or 17 to cause them to drop into engaging position with the ledge 15.

The latch 16 and the latch 17 are both pivoted to the door at a common pivot center and with a common pivot pin 19. The latches

both extend within the space between the flanges or webs 9 of the door stiffener 6 and swing in parallel planes, one just outside of the other, and both parallel with the plane of the door plate. This comprises a desirable arrangement of the parts as the latch members do not occupy additional space beyond the limits of the channel and also are kept close to the door plate for greater efficiency. In order to provide a stiff and substantially pivot construction, a pivot bracket 20 is provided. This has a plate portion 21 which spans from one return or outstanding flange 10 to the other, the bracket as a whole being secured to the spreader by means of rivets 22 which pass through these return or outstanding flanges. The bracket 20 has a portion 23 thereof arranged to extend inwardly toward the web 7 and to fit between the flanges or webs 9 of the channel or U-shaped section of the door stiffening member. This portion 23 is arranged with a pierced inner wall through which the pivot pin 19 is inserted. The pivot ends of the latches 16 and 17 are inserted between the outer face of the bracket 20 and this inner wall of the portion 23 and when the pin 19 is inserted through the said pierced opening it passes through the fulcrum holes of these latches. The plate portion 21 of the bracket is also provided with a partially pierced boss 24 on its inner face into which one end of the pin 19 may seat. As this boss is not pierced entirely through, the pin cannot work outwardly, and when the bracket as a whole is riveted to the stiffening member 6 the pin is prevented from working inwardly by contact with the web 7. This comprises a neat, strong and inexpensive manner of pivoting the latches to the door stiffening member.

When the door is pushed to partially closed position the innermost latch 16 is arranged to engage with the ledge 15 and thereby hold the door in a partially closed position. The latch 17 is provided with an extension 25 arranged to pass around and overlie the side of the car. This extension is provided with an aperture 26 through which a removable door-closing lever or pry 27 may be inserted to force the door from partially closed to fully closed position. The aperture 26 serves as a seat for the lever and the off-set in the bracket 14 may serve as a fulcrum for the inner end of the lever when it is operated as a pry to force the door shut. When the door is forced shut by this or other means the outer or final latch 17 is swung downwardly into engagement with the ledge 15, thereby holding the door in fully closed position.

The latch 16 is slightly removed from the outer face of the door but not sufficiently so to entirely clear the outer edge of the side flange 11. Accordingly this flange is notched at 28 to provide a way for the swinging of this latch 16. The upper edge of the latch 16 is also depressed slightly at 29

to provide necessary clearance between the latch and the upper flange or web 9 of the channel 6 when the latch is lifted upwardly to release the door. The outer latch is similarly depressed at 34. It is preferable that the closed door be supported near or upon the side flange 11 and to this end the outer latch 17 is provided with an extension 30 along its lower edge which extension is adapted when the door is closed, to seat directly against the flange 11 at 31 which is immediately below the cut-out portion 28 thereof. This construction also prevents the latch from dropping below the approach or run 18.

In order to lock the latch 17 in engaged position an eccentric cam 32 is pivoted to the bracket 12 immediately above the latch. When this is driven against the portion 25 of the latch 17 an effective lock is thereby provided to prevent disengagement of the latch 17 from the latch 15. The latch 17 in turn locks the latch 16 by means of the extension or lip 33 formed along the top edge of the latch 17. This lip is adapted to overlie the top of the latch 16, thereby interlocking the two latches in such manner that the preliminary latch cannot be withdrawn until the outer latch 17 has first been withdrawn, so that in this way the eccentric cam 32 will serve to lock both latches.

As trouble has been experienced by workmen locking the door when supported in only a preliminary or partial position of closure, the arrangement and dimensions of the arm 25 and the eccentric locking cam or keeper 32 are such that, when the door is supported in partially closed position by the pivoted latch 16, the cam or keeper 32 cannot be rotated into holding engagement with the arm 25 of the latch 17. Upon the door being moved to fully closed position, the latch 17 will drop behind the ledge 15 of the bracket or hook 12. With the latch in this position the cam 32 may be readily rotated into locking engagement with the arm 25, as clearly shown in Figure 1 of the drawings.

I have thus described an embodiment of my invention. Other embodiments are contemplated within the scope of the appended claims without departing from the spirit thereof.

What is claimed is:

1. In a railway car, a door, a stiffening member secured to the outer face of the door, the same being of channel cross-section with the web thereof lying parallel with the door and with the flanges outstanding therefrom, a ledge carried by the car body adjacent the door, and a movable member carried by the door and adapted to engage the said ledge to hold the door closed, the said movable member lying between the flanges of the said stiffening member.

2. In a railway car, a door, a stiffening member secured to the outer face of the door,

the same being of channel cross-section with a web portion lying parallel with the door and with flange portions outstanding from opposite edges of the web, the outer edges of the flange portions carrying return flanges disposed in a plane parallel with that of the web portion, a pivot bracket mounted upon the stiffening member, the same including a plate portion spanning across the outer edges 5 of the flange portions of the same and secured to the said return flanges, and a door locking member pivoted to said pivot bracket.

3. A railway car having a door with an outstanding flange formed along one of its edges, 15 a plurality of pivoted door-supporting members carried by the door on line with said flange, a portion of said flange being cut away to clear one of said pivoted members, and another one thereof being arranged to seat 20 against the edge of said flange to support the door, and means carried by the car body for supporting cooperation with said last mentioned pivoted member.

4. A railway car having a door, a pair of latches pivoted upon the door, one thereof adapted to support the door in partly closed and the other thereof in fully closed position, a ledge on the car body arranged for engagement by the said latches, one of said latches 25 having a shoulder adapted to overlie and lock the other latch.

5. A railway car having a door with a latch member pivoted thereupon, a member carried by the car body adjacent said latch adapted for cooperation with the latch to hold the door shut, the outer end of the latch being bent in a direction angular to the main portion thereof to lie in a plane substantially parallel with the side of the car, the said bent 40 portion of the latch having means adapted to form a seat for a removable door-prying lever.

6. A railway car having a door with a latch member pivoted thereupon, a member carried by the car body adjacent said latch adapted for co-operation with the latch to hold the door shut, the outer end of said latch being bent in a direction angular to the main portion 45 thereof to overlie a fixed portion of the car body, said bent portion being provided with a seat adapted to receive a removable door-prying lever, and means on the said fixed portion of the car body adapted to form a fulcrum for the lever.

55 7. A railway car having a door, said door being provided with a pair of pivoted latches adapted to swing in parallel planes, a latch-engaging ledge formed on the car body, one of said latches being adapted to engage said ledge to hold the door in partly closed position and the other thereof being adapted to engage said ledge to hold the door in fully closed position.

8. A railway car having a door, means for supporting said door in closed position, said

means embodying a pair of movable latches and fixed means, one of said latches being cooperable with the fixed means to support the door in partially closed position and the other of said latches being cooperable with the fixed means to support the door in fully closed position, means for locking said last named latch in door supporting position, and means carried by said last named latch overlapping the outer edge of said first named latch to prevent unlocking movement of the latter.

9. A railway car having a door, a door supporting latch pivoted upon said door to swing in a plane substantially parallel thereto, 80 a ledge carried by the car body adjacent the door adapted for supporting cooperation with such latch and a latch-locking member pivoted upon the car body adjacent said ledge, the same being adapted to hold 85 the latch in engagement with said ledge.

10. A railway car having a door, the same being provided with a pair of latch members one arranged in advance of the other, a ledge formed upon the car body in position to be 90 engaged by either of said latches, one of said latches being adapted to support the door in a partly closed position and the other in fully closed position, and a cam adapted to lock the last mentioned latch in engaged position.

11. A railway car having a door, means for supporting the door in partly closed or in fully closed position, said means including a ledge and a latch pivoted to swing in a plane substantially parallel to that of the door 100 when in closed position, one carried by the car body and the other by the door, the latch being adapted to engage the ledge to hold the door in partly closed position, and a member adapted to be moved in position between the 105 latch and the ledge to hold the door in a further closed position.

12. A railway car having a door, means for supporting the door in partly closed and in fully closed position, the same including a 110 ledge element and a latch element pivoted to move in a plane substantially parallel to that of the door when closed, one carried by the car body and the other by the door, the latch element being adapted to swing into 115 engaged position with the ledge element to support the door in partly closed position, and a second latch element adapted to swing into a position between the ledge and the first mentioned latch to support the door in fully 120 closed position.

13. A railway car having a door with two latch members mounted thereupon, one adapted to support the door in a partly closed position and the other in a fully closed position, 125 a ledge carried by the car body adapted for engagement by either of the said latches, and means carried by one latch adapted for use in forcing the door from one of said positions to the other.

14. A railway car having a door, a ledge formed upon a fixed portion of the car body adjacent said door, and a pivoted latching member carried by the door adapted to engage the ledge to support the door in closed position, the ledge member having a portion forming a fulcrum for a removable door prying lever.
15. A railway car having a door, a ledge formed upon a fixed portion of the car body adjacent said door, and a pivoted latching member carried by the door adapted to engage the ledge to support the door in closed position, the latch member having means for accommodating a removable door prying lever.
16. A railway car having a door, a ledge affixed to the car body adjacent said door, a pivoted latch carried by the door adjacent said ledge and adapted to engage same to support the door, one of the same having a fulcrum and the other a seat adapted to receive and accommodate a removable door prying lever.
17. A railway car having a door provided with a marginal flange, a ledge affixed to the car body adjacent the seat attached to the door, a pair of latch members carried by the door either of which is adapted to engage said ledge to hold the door in a partly closed or fully closed position, a portion of such flange being cut away to clear one of said latches, the other thereof being adapted to overlie and seat against said flange.
18. A railway car having a door, a fixed hook carried by the car body, a pivoted latch carried by the door for cooperation with the hook to support the door in closed position, and a pivotally mounted eccentric locking cam carried by the car body adapted to engage the latch to hold the latter in engagement with the hook, the pivotal axis of said cam being arranged at an angle to the pivotal axis of the latch.
19. In a railway car, a door, and means for supporting the door in closed position involving a fixed locking member, and a locking member movable into engagement with the fixed locking means, and a keeper for maintaining the outer end of the movable member in locked position, the movable locking member extending at an angle to the portion thereof engageable with the fixed locking means for engagement by said keeper.
20. A railway car having a door, a fixed locking member mounted on the car body, a movable locking member mounted on the door and arranged to move in a plane parallel to the plane of the latter for cooperating with said fixed locking member to support the door in closed position, and a keeper for maintaining the members in locked position, the movable locking member being provided with an arm overlapping the outer face of the fixed locking member and engageable by the keeper.
21. A railway car having a discharge opening, a door for closing said opening, a fixed hook mounted on the car body and a pivoted latch carried by the door cooperable with the hook for supporting the door in closed position, the plane of operation of the latch being substantially parallel with the plane of the door and the outer end of said latch terminating in an offset portion extending along and spaced outwardly from the car side.
22. A railway car having a discharge opening, a door for closing said opening, and mechanism for preventing an opening movement of the door, said mechanism involving fixed locking means and pivotally mounted locking means cooperating therewith to maintain the door in partly closed and fully closed position, one of said means being mounted upon the car body and the other being mounted on the door, and pivotally mounted cam means for cooperating with said pivotally mounted locking means to maintain the latter in locked relation to said fixed locking means, one of said pivoted devices being mounted upon the door and the other being mounted on the car body, and said cam being adapted to move into locking engagement with the said pivoted locking device only when the door is in fully closed position.
23. A railway car having a discharge opening, a door for closing said opening, and mechanism for supporting the door in a plurality of positions of closure involving fixed locking means and pivotal locking means, one of said means being mounted on the car body and the other on the door, and one of said means being provided with a plurality of faces for cooperation with the other of said means to support the door in partially closed or in fully closed position, and a movable member mounted on the fixed locking means, said movable member being adapted to move into engagement with the pivoted locking means to maintain the latter in locked position only when the door is supported in fully closed position.
24. A railway car, a door, mechanism for supporting the door in a plurality of positions of closure involving fixed locking means mounted on the car and pivoted locking means carried by the door, one of said means being provided with a plurality of faces to cooperate with the other of said locking means to support the door either in partially closed or in fully closed position, and a movable member carried by the car body, the same being so formed and arranged that it may be moved into retaining engagement with the pivoted locking means when the latter is engaged with the fixed locking means for holding the door in fully closed position, and so

that it cannot be moved into retaining engagement with the pivoted locking means when the latter is in engagement with the fixed locking means for holding the door in partially closed position.

25. A railway car, a door, mechanism for supporting the door in a plurality of positions of closure involving a fixed locking means carried by the car and pivoted locking means carried by the door, one of said means being provided with a plurality of faces to

cooperate with the other of said locking means to support the door in partially closed or fully closed position, and an eccentric locking cam pivotally mounted on the fixed locking means and adapted to move into locking engagement with the pivoted locking means only when the door is supported in fully closed position. 15

In testimony whereof I affix my signature.
